UNITED STATES PATENT OFFICE.

EMIL W. MUNDT, OF NEW YORK, N. Y.

CURTAIN-PIN.

Specification of Letters Patent. Patented Dec. 15, 1914.

1,121,391.

Application filed May 13, 1914. Serial No. 838,289.

To all whom it may concern:

Be it known that I, EMIL W. MUNDT, a citizen of the United States, and a resident of the city of New York, borough of the Bronx, in the county of the Bronx and State of New York, have invented a new and Improved Curtain-Pin, of which the following is a full, clear, and exact description.

10 This invention relates to fastening devices and has particular reference to hooks or pins adapted primarily for securing lace curtains or the like.

15 Among the objects of the invention are, first, to provide a curtain pin of a simple and cheap construction of a nature serving to prevent the fabric from becoming caught or snarled in any manner; and, secondly, to provide improved locking means not only 20 for the hook portion but also for the pin.

The foregoing and other objects of the invention will hereinafter be more fully described and claimed and illustrated in the drawings forming a part of this specification 25 in which like characters of reference indicate corresponding parts in both the views, and in which—

Figure 1 is a perspective view showing the parts in normal closed position; and 30 Fig. 2 is an edge view of the same.

The several parts of the device may be made of any suitable materials, and the relative sizes and proportions, as well as the general design of the mechanism, may be varied to a considerable extent without departing from the spirit of the invention hereinafter more fully described and specifically claimed.

40 My invention in its preferred form comprises a device formed preferably from a single piece of wire and so bent as to form at one end a straight bar pin 10 and at the other end a peculiar form of keeper 11. The intermediate portions of the piece of wire are formed into a hook 12 and a 45 spring 13. The keeper 11 extends downwardly at an angle from a frame bar 14 which may lie substantially in the same vertical plane as the pin 10, and the keeper portion is bent laterally at the bottom from 50 said plane and thence upwardly, forming a loop 11^a at the bottom, and thence bent again forming a loop 11^b in a plane oblique to the plane of the bar 14 and pin 10 and with the free end of the metal bent substantially parallel to the parts just described,

forming a loop 11^c at the bottom substantially against the loop 11^a. The free end of the keeper projects upwardly toward the shoulder 15 and is adapted to move bodily 60 to a certain extent laterally with respect to the vertical plane of the pin so as to allow the pin to pass either inwardly or outwardly past the hump 11^d which is formed in the keeper between the loop 11^b and the 65 bottom thereof and which extends inwardly toward the plane of the pin aforesaid and as shown in Fig. 2. In other words, that portion of the keeper between the loops 11^b and 11^c tends to obstruct the passage of the 70 pin in or out of the keeper, but the elasticity of the keeper, especially the free end thereof, will permit the pin to be forced past the hump 11^d.

The hook 12 of the device comprises a 75 shank 16 having two portions of the wire twisted together, making a stiff structure, and above the twisted portion the two wires are formed into right and left coils 17. The wires emerge from the coils in close relation to each other, and are thence bent into the hook 11, the point 12' thereof making the connection between the two wire portions. The coils 17 coöperate with the tongue portion of the hook 12 to form a 85 spring lock for the hanger or ring (not shown) from which the hook 12 is suspended in practice. In other words, the coils 17 are adapted to bear loosely against the rear faces of the portions of the wire which form 90 the loop 12' of the hook and prevent accidental displacement or release of the curtain pin from its support.

A second frame bar 14' leads from the shank 16 to the spring 13. The spring is 95 of a form and nature similar to other devices of this general character, but instead of the pin leading directly horizontally from the spring, it extends downwardly at 10^a forming a substantially square shoulder 100 10^b which serves as a stop or abutment for the fabric through which the pin is adapted to pass, thereby preventing the fabric from catching into and being torn by the 105 spring 13.

Having thus described my invention, I claim as new and desire to secure by Letters Patent:—

1. In a fastening device of the character set forth, the combination of a frame, a pin 110 having spring connection to the frame in substantially the same vertical plane as the

frame, and a keeper for the point of the pin, said keeper comprising a portion of the material as an extension of the frame bent downwardly in the plane aforesaid, 5 thence laterally from said plane and thence bent again at an oblique angle to said plane, and thence downwardly forming a pair of loops to support the pin, one of said loops being movable bodily laterally of the frame 10 of the pin and frame independently of the other loop.

2. The herein described curtain pin comprising a frame, a pin lying substantially in the same vertical plane as the frame, and a 15 keeper for the point of the pin, said keeper being formed as an extension of one portion of said frame, said portion being bent down-

wardly around the pin, thence upwardly and thence downwardly, forming a loop at an oblique angle to the plane of the pin 20 aforesaid, and thence bent downwardly around the pin in a reverse direction to the first mentioned loop, the portion of the keeper between the upper loop thereof and the bottom loop being bent inwardly toward 25 the plane of the pin and frame forming a lock for the pin point.

In testimony whereof I have signed my name to this specification in the presence of two subscribing witnesses.

EMIL W. MUNDT.
